US00D532369S

(12) **United States Design Patent** (10) Patent No.: **US D532,369 S**
Shimizu (45) Date of Patent: **** Nov. 21, 2006**

(54) **BATTERY CHARGER**

(75) Inventor: **Minoru Shimizu**, Tokyo (JP)

(73) Assignee: **Sony Computer Entertainment Inc.**,
Tokyo (JP)

(**) Term: **14 Years**

(21) Appl. No.: **29/239,312**

(22) Filed: **Sep. 29, 2005**

(30) **Foreign Application Priority Data**

Mar. 31, 2005 (JP) D2005-009640

(51) **LOC (8) Cl. 13-02**

(52) **U.S. Cl. D13/108**

(58) **Field of Classification Search** D13/107-110,
D13/118-119, 184; D14/251, 253, 432, 434;
320/107-115

See application file for complete search history.

(57) **CLAIM**

The ornamental design for a battery charger, as shown and described.

DESCRIPTION

FIG. 1 is a perspective view of a battery charger showing my new design; and,

FIG. 2 is a front elevational view thereof.

The broken lines depicted in FIGS. 1-2 form no part of the claimed design.

1 Claim, 2 Drawing Sheets

FIG. 1

FIG. 2
